UNITED STATES PATENT OFFICE.

WILLIAM G. ESMOND, OF STRATFORD, CONNECTICUT.

GOLF CLUB.

Application filed December 23, 1922. Serial No. 608,712.

To all whom it may concern:

Be it known that WILLIAM G. ESMOND, a citizen of the United States, and resident of Stratford, in the county of Fairfield, and State of Connecticut, has invented certain new and useful Improvements in Golf Clubs, of which the following is a specification.

This invention relates to a golf club, and has more especial reference to a "sand spoon" golf club.

The broad object of the invention is to provide a golf club the striking face of which will be constructed to exert an impact against a ball during a stroke tending to lift the ball from an imbedded position in sand, or the like, and the heel of which will be constructed to offer no resistance to the stroke by interference with the ground or sand beneath the ball. A more specific object is to provide a golf club, designed to enter sand, or the like, during a stroke to lift an imbedded ball therefrom, the striking part of which consists of a striking face constructed to have, in effect, two locations of impact against a ball, one situated at a lower and more advanced position on the ball than the other, and a heel the forward edge of which is adapted to cooperate with the striking face in cutting-away sand adjacent the ball and the rearward portion of which slants from the cutting-edge toward the shaft of the golf club to offer no interference during the stroke with the surface of the ground or sand beneath the ball, the lower and advanced location of impact of the striking face with the ball being adapted to exert a lifting blow against the ball during a stroke while the other location of impact exerts a normal forward driving blow, whereby a resultant force against the ball tending to simultaneously lift and drive the same will be obtained.

With the above and other objects in view, the invention comprises the construction, arrangement and combination of parts as now to be described and claimed, but it is to be understood that the disclosure is merely illustrative of the principles of the invention, slight changes in details of construction being permissible so long as within the scope of the appended claim.

In the accompanying drawing,

Fig. 1 is a rear elevational view of the striking part of the improved golf club;

Fig. 2 is an elevational view looking directly at the striking face; and

Fig. 3 is a sectional view on line 3—3 in Fig. 1, suggesting the manner in which the golf club functions.

Referring more particularly to Fig. 3, reference character A denotes the ground or sand level, and B denotes a golf ball imbedded in the ground or sand.

The golf club of the invention consists of a shaft 10 and a driving part represented 60 11. The driving part is desirably of metal and the golf club shown is for a left handed player, although the invention applies 65 equally well to a right handed club.

The body 12 of the driving part may be of any construction suitable for properly disposing the weight of the driving part to best accomplish the object for which the club has been designed. The striking face may have the angle and configuration of an ordinary mashie-niblick for a considerable portion of its depth, denoted 13, or the portion 13 may have a different angle and configuration, depending upon the preference of the player. A part of said depth, however, denoted 14, disposed at the lower portion of the striking face, slants forwardly from the portion 13 to be situated in advance of said portion 13 and at greater angle to the shaft of 70 the golf club. Preferably, the full length of 75 the whole of the striking face constitutes a plane surface.

The part of the width denoted 14 of the striking face constitutes, as disclosed, a plane surface into which the plane surface 90 of the portion 13 of the width gently merges. The arrangement here may also suit the preference of the player.

The forward edge 15 of the body 12 of the driving part is constructed to cooperate with 95 the striking face in cutting-away sand adjacent and to the rear of the ball, and to this end said forward edge may be of the configuration shown or of some other suitable configuration. The heel 16 of the body 100 12 merges at its forward portion into the cutting-edge 15, and the rearward portion of the heel slants from the cutting-edge toward the shaft of the golf club to offer no interference during a stroke with the surface of 105 the ground or sand beneath the ball.

As will be most clear from Fig. 3, wherein I disclose the golf ball B partially imbedded in ground or sand having the level A, the dotted line C denotes the cut in the ground 110 or sand made by the cutting-edge and striking face during a stroke. The lower ex-

tremity of the portion 13 of the striking face is shown in engagement with the ball slightly below the center thereof, the upper extremity of the part 14 of said striking face is shown in engagement with the ball at a lower, advanced position, and the heel 16 is shown as having cleared the dotted line C indicating the cut in the ground or sand defined by the cutting-edge 15.

10 Evidently, the location of impact of the portion 13 of the striking face with the ball is adapted to exert a normal forward driving blow, and the location of impact of the part 14 is adapted to exert a lifting blow 15 against the ball. Consequently, the relative arrangement of the portion 13 and part 14 can determine the resultant force applied to the ball during a stroke to simultaneously lift and drive the same. As disclosed, this 20 resultant force is capable of driving the ball from the ground or sand at an angle of 45°. Note the arrow in Fig. 3.

Actually, the location of merger of the portion 13 with the part 14 of the striking face may constitute a plane surface defining the location of impact with the ball. Nevertheless, there will be in effect two locations of impact against a ball, imparting the resultant force determined by the relative arrangement of the portion 13 and part 14.

30 It will be apparent that the golf club as illustrated and described will be an effective sand spoon for lifting and driving a ball no

matter to what extent the ball is imbedded, so long as the ball is visible (as required by 35 the rules of golf). Furthermore, it will be apparent that the novel golf club contemplates the employment of skill by the player, the lifting and driving of the ball by means of the improved striking face requiring to 40 be supplemented, to obtain the particular result at the time desired, by wrist movements, etc., of the golfer. But with the present club wrist movements need not be 45 abnormal.

Having thus fully described the invention, what I claim as new and desire to secure by Letters Patent is:

A golf club driving part comprising a body defining a striking face and a heel 50 slanting from the lower edge of said striking face toward the shaft of said golf club, the striking face including a portion set at an angle with respect to the shaft for normal forward driving of a ball, and a part 55 below said portion, in advance thereof, and set at greater angle to said shaft to exert a lifting blow against said ball, whereby a resultant force against the ball tending to simultaneously lift and drive the same forwardly in normal manner will be obtained.

Signed at Bridgeport, in the county of Fairfield, and State of Connecticut, this 22nd day of December, A. D. 1922.

WILLIAM G. ESMOND.
